UNITED STATES PATENT OFFICE.

GEORGE A. WYETH, OF NEW YORK, N. Y.

COMBINED CAP-EXTRACTOR AND SANITARY BOTTLE-CLOSURE.

1,372,468.

Specification of Letters Patent. Patented Mar. 22, 1921.

Application filed September 4, 1919. Serial No. 321,691.

To all whom it may concern:

Be it known that I, GEORGE A. WYETH, a citizen of the United States, and resident of New York city, in the county of New York 5 and State of New York, have invented certain new and useful Improvements in Combined Cap-Extractors and Sanitary Bottle-Closures, of which the following is a specification.

10 My invention relates in general to a combined cap extractor and sanitary bottle closure of the type of such devices which are designed to engage and remove from milk bottles and the like, the paper disks usually 15 employed as closures on such bottles, and to furnish a sanitary means of closure to bottles thereby preventing contamination to contents.

The primary object of the invention is to 20 provide a simple means for readily removing the usual paper cap closures and at the same time to provide a simple form of metallic closure which can be quickly secured to and removed from the mouth of the bottle and 25 which will utilize the usual paper disk as a replaceable gasket to insure the sealing of the bottle and coat therewith to effect a closure capable of resisting to a large degree any accidental removal of the paper 30 gasket.

Such construction, as heretofore designed, includes a cap engaging member designed to 35 make an incision through the cap for the purpose of anchoring the closure to the cap and for the purpose of facilitating the withdrawing of the paper cap from the bottle. These cap withdrawing constructions, however, have been objectionable in that they 40 are apt to cause the paper cap especially if frail, to buckle inwardly against the contents of the bottle and under some conditions are apt to tear the cap thus destroying its value as a sealing element.

Accordingly, another object of the invention 45 is to furnish an absolutely sanitary closure for top of bottles, completely covering the entire pouring surface of same and thereby preventing contamination by flies, insects, dirty hands, etc. Further, another 50 object of the invention is to provide a type of cap anchor which will form a clear incision through the cap and which will coat with the incision thus formed to secure the paper cap to the body portion of the anchor carrying closure.

Still another object of the invention is to

provide a device of the type above outlined which can be manufactured economically so that it can be marketed at low cost. Featur- 60 ing this phase of the invention there is contemplated the providing of a one-piece sheet metal stamping in which one or more anchors, and if desired certain spring clips for holding the closure to the bottle, are formed by suitably slitting the sheet metal 65 and forming the anchors and clips in the act of pressing the device to shape.

Various other objects and advantages of the invention will be in part obvious from an inspection of the accompanying drawings 70 and in part will be more fully set forth in the following particular description of one form of mechanism embodying my invention, and the invention also consists in certain new and novel features of construction 75 and combination of parts hereinafter set forth and claimed.

In the accompanying drawings:—

Figure 1 is a perspective rim of the upper portion of a bottle showing a preferred 80 embodiment of the invention positioned thereon;

Fig. 2 is a vertical sectional view taken centrally through the device shown in Fig. 1; and

Fig. 3 is an enlarged detail view of part of the closure shown in the preceding figure and inverted to show one of the anchors.

In the drawings, there is shown a bottle neck 10 provided with a throat 11, and the 90 upper edge of which neck is rounded to provide a mouth 12. The neck is provided with the usual countersunk seat 13 positioned within the throat and spaced downwardly from the mouth 12. A paper cap 14 is positioned on the seat and acts to close the throat as is usual in some jars and bottle constructions such as the milk bottles in general use.

The closure 15 particularly forming the 100 subject matter of this invention is a one-piece, sheet metal stamping which is made of as thin a metal as will withstand the strains to which such devices are intended to be subjected. The closure is formed in general 105 of a body portion which includes a counter-sunk central disk 16 which fits flat on top of the paper cap 14 and has a diameter substantially equal to that of the paper cap so that the disk and cap coat to form a double-layer thickness of material across the throat 110 of the bottle as shown in Fig. 2. A periph-

eral flange 17 outlines the disk 16 and rounds upwardly and outwardly therefrom so as to inclose the mouth 12 within the groove 17 formed by the flange on the under side of 5 the closure. A plurality of holding clips 18 herein shown to be four in number and equally spaced about the closure constitute extensions from the lower edge of the peripheral flange and constitute guiding 10 means for locating the closure in position on the bottle as shown in Fig. 1. Each of the clips are provided within its outlines with downwardly converging slits 19 joining at their lower end to form spring fingers 20. 15 These spring fingers are pressed inwardly so that they will engage the side of the neck below the mouth and hold the closure resiliently in position and against accidental knocks which may tend to displace the same 20 and accommodate different sized bottles. The central disk is likewise slotted at three circumferentially spaced apart points to form pointed downwardly extending projections 21 hereinafter referred to as 25 anchors. It is understood that these anchors are formed by slitting the body portion of the container and bending the anchors at right angles to the plane of the disk. These anchors are V-shaped in horizontal 30 cross-section and with their pointed ends act on the paper disk when forced into engagement therewith, to form a V-shaped incision in the disk. This causes the disk to adhere firmly to the anchors. The edges of the 35 anchors are serrated as shown at 22 which serrations have the effect of preventing the easy withdrawal of the closure from the cap when an attempt is made to elevate the cap by lifting the closure as hereinafter more 40 fully described. One anchor is sufficient to attach the closure to the cap, and to elevate the same but the three anchors disclosed are preferred. Elevators 23 in the form of diametrically extending and outwardly exposed tabs project from opposite sides of 45 the peripheral flange and are preferably disposed in alinement with the anchor when but one anchor is used.

This relation of elevators to anchor is of 50 advantage especially when a resilient form of closure is used for, as the closure is lifted off the bottle, the tendency of the anchors is to spring outwardly toward the periphery thus holding the paper cap more firmly and 55 insuring the positive withdrawing of the same from the bottle.

As the metallic closure firmly engages the bottle at the side of the neck, any tendency of the bottle, as in turning over to displace 60 the paper cap is resisted by the closure, thus providing a sanitary form of closure which can be used repeatedly while the paper cap can be replaced with each new filling of the bottle.

65 As the entire closure can be formed from

one-piece by a simple stamping operation there is effected a material saving in the manufacture and cost.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim—

1. A one-piece closure for a bottle of the type usually closed with a paper cap, said closure including a central disk, a peripheral flange outlining said disk and adapted to fit over the mouth of the bottle, a holding clip depending from the outer edge of said flange and adapted to engage the outside of the bottle, and an anchor depending from said central disk and adapted to perforate the paper cap, said anchor being V-shaped in cross section in a plane parallel to the disk 90 to form a V-shaped incision in the paper cap.

2. A one-piece closure for a bottle of the type usually closed with a paper cap, said closure including a central disk, a peripheral flange outlining said disk and adapted to fit over the mouth of the bottle, an anchor depending from said central disk and adapted to perforate the paper cap, said anchor being V-shaped in cross section to form a V- 100 shaped incision in the paper cap and having serrated edges.

3. A one-piece sheet metal closure for a bottle including a peripheral flange adapted to fit over the mouth of the bottle, a spring clip depending from said flange, provided with a pair of slits forming a spring finger adapted to bear on the outside of the bottle to hold the closure in place and said closure provided with a pair of slits forming a 110 pointed cap engaging anchor.

4. A one-piece sheet metal closure for a bottle including a central cap engaging disk and a peripheral flange integral therewith, and outlining the same, said closure having 115 a plurality of slits cut therein, the metal between certain of said slits being bent from the slotted portion to form spring clips for engaging the bottle, the metal between certain other slits being bent from other slotted 120 portions to form a cap engaging anchor.

5. A one-piece sheet metal closure for a bottle including a cap-engaging disk provided with a pair of slots spaced from the edge and converging to a point to form a 125 pointed finger, said finger being pressed from the disk at right angles thereto to form an anchor adapted to perforate the usual paper caps constituting the closure for certain types of bottles.

6. A one-piece sheet metal closure for a bottle including a cap-engaging disk provided with a pair of slots converging to a point to form a pointed finger, said finger being pressed from the disk to form an anchor adapted to perforate the usual paper caps constituting the closure for certain types of bottles, said finger being V-shaped in cross-section to form a V-shaped incision in the paper cap. 10
7. A one-piece sheet metal closure for a bottle including a cap-engaging disk provided with a pair of slots converging to a point to form a pointed finger, said finger being pressed from the disk to form an anchor adapted to perforate the usual paper caps constituting the closure for certain types of bottles, said finger being V-shaped 15
- in cross-section to form a V-shaped incision in the paper cap, and having its edges serrated. 20
8. A one-piece sheet metal closure for a bottle including a central disk, a peripheral flange outlining the disk and provided with an extension from the free edge thereof, said extension and the portion of the flange adjacent thereto being slitted from adjacent the disk outwardly toward the outer end of the extension to form a long spring finger for engaging the outer side of the bottle. 25
- Signed at New York city in the county of New York and State of New York this 27th day of August, A. D. 1919. 30

GEORGE A. WYETH.
